UNITED STATES PATENT OFFICE.

MIGUEL A. CARVAJAL DE CASTRO, OF BOGOTA, COLOMBIA.

ELECTRIC POST LAMP.

Application filed October 24, 1927. Serial No. 228,165.

This invention relates to an electric post lamp and has for one of its objects the provision of a reflector attachment which may be detachably mounted on a flashlight.

Another object of my invention is the provision of an ornamental doll attachment for flash lights having a reflector therein adapted to direct rays of light downwardly when the flashlight is disposed in upright position on a horizontal surface.

A further object of my invention is the provision of an ornamental doll attachment for flashlights comprising a cap adapted to replace the lens cap of an ordinary flashlight, having a doll pivotally mounted thereon and a reflector in the doll adapted to be adjustably positioned relative to the flashlight for suitably directing rays of light downwardly at an inclination to the casing of the flashlight.

A still further object of my invention is the provision of an ornamental doll comprising a reflector and an electric light bulb adapted to be pivotally connected with a flashlight casing, the bulb being electrically connected with the battery of the flashlight casing.

Other objects will appear hereinafter, the novel features and combinations being more clearly set forth in the appended claims.

In the drawings:

Fig. 1 is a perspective view of my invention.

Fig. 2 is a sectional view taken on the line 2—2 of Fig. 1.

Fig. 3 is a perspective view of a modification of my invention.

Fig. 4 is a sectional view taken on the line 4—4 of Fig. 3.

Fig. 5 is a perspective view illustrating my invention in one adjusted position.

Fig. 6 is a perspective view illustrating my invention in another adjusted position.

Referring particularly to the drawing, the numeral 10 designates a flashlight casing comprising an end cap 11 having a lens 12 therein. A detachable band 13 is disposed around the cap 11 and the ends thereof are clamped together by a bolt 14 mounted in apertures in flanges 15 and 16 on the extremities of the band 13.

A support 17 is rigidly attached to the band 13 and extends upwardly therefrom. The support 17 is offset as at 18 and comprises an inclined section 19. A torso 20 of a doll 21 preferably comprising wood is attached to the upper end of the inclined section 19, as

shown in Figs. 1, and 2. A circular reflector 22 is rigidly attached to the inclined portion 19 of the support 17 by a bracket 23 and is disposed directly below the torso 20. It should be understood that the torso 20 is provided with a garment such as ordinarily employed on dolls and that the skirt 24 of the garment is retained in extended position by engagement with the edge or periphery of the reflector 22. When the flashlight, which is of ordinary construction is lighted, the rays of light emitted from the lens 12 are directed upon the reflector 22 and are redirected downwardly thereby for illuminating a portion of the horizontal surface upon which the flashlight is rested.

It should be understood that the torso 20 may comprise transparent material and that apertures 25 may be provided in the reflector 22 to permit some of the light from the flashlight to pass therethrough for illuminating the entire doll.

In the modified form of my invention illustrated in Figs. 3 to 6 inclusive, the flashlight casing 10' is provided with a special cap 26 having a slot 27 therein, a link 28 is pivotally mounted in the slot 27 and is adapted to frictionally engage the resilient spacing member 29 which preferably comprises strips of rubber mounted on the sides of the slot 27. The upper extremity of the link 28 is rounded and is provided with a pivotally attached platform 30. The platform 30 comprises spaced-apart brackets 31 which are adapted to be held in frictional engagement with the sides of the link 28 by the bolt 32 which is disposed through registering apertures in the link and brackets.

The platform 30 is adapted to support a doll which comprises leg members 33 attached to a support comprising a horizontal section 34. The end portions 34' and 35' of the horizontal support 34 are disposed upwardly at an inclination to the intermediate portion thereof and are attached to torso 35 of the doll. The torso 35 is provided with an electric light socket 36 in which a flashlight bulb 36' is disposed and a reflector 37 of circular shape is mounted directly below the torso 35; being attached at its periphery to the inclined sides 34' and 35' of the support. It should be understood that a garment is mounted on the torso 35 comprising a skirt 38 which depends therefrom over the reflector and support as illustrated in Fig. 3.

An electric contact member 39 is mounted

on the top wall of the cap 26 and is adapted to engage the terminal 40 of a battery 41 disposed within the casing 10'. The contact member 31 is electrically connected with one 5 terminal of the bulb 36' by a wire 42 and the other terminal of the bulb is electrically connected by a wire 43 with the casing 10' which in turn is electrically connected with the other terminal of the battery. It should be 10 understood that the wires 42 and 43 are of sufficient length to permit the adjustment of the doll hereinafter set forth.

As illustrated in Fig. 5 the link 28 may be disposed diagonally while retaining the doll 15 in upright vertical position thus positioning the doll to one side of the center of the casing 10' so as to cause the light emitted from the bulb 36' to be projected downwardly by the reflector 37 on that portion of the surface supporting the flashlight casing, adjacent the 20 casing. The light may in this manner be directed upon a book or paper as desired.

In the position shown in Fig. 6 both the 25 link and the doll are disposed at an inclination to the casing 10' and the reflector 37 is adapted to direct the light emitted from the bulb 30' downwardly at an inclination to the casing 10'. With the reflector positioned as 30 illustrated in Fig. 6 it is possible to direct the rays of light outwardly from beneath the skirt of the doll as desired, while retaining the casing 10' in vertical upright position.

Having thus fully shown and described an 35 embodiment of my invention what is desired to be secured by Letters Patent of the United States is:

1. An electric post lamp of the class described comprising a flashlight, an attachment mounted on the casing of said flashlight, 40 a doll supported by said attachment and a reflector mounted on said attachment disposed below the torso of said doll and beneath the skirt thereof adapted to direct rays 45 of light downwardly.
2. An electric post lamp of the class described comprising an ornamental doll mounted on a flashlight and a reflector disposed beneath the skirt of said doll adapted to retain the skirt in extended position and to 50 direct rays of light from said flashlight downwardly.

3. An attachment for flashlights comprising a band adapted to be removably mounted on the lens cap of a flashlight, a support on 55 said band disposed above the lens of said flashlight, a doll comprising a torso mounted on the upper end of said support, a reflector

attached to said support and positioned below said torso, and a skirt attached to said torso and disposed around said reflector adapted 60 to be retained in extended position by said reflector, said reflector being adapted to direct rays of light from said flashlight downwardly when the latter is disposed in upright 65 position.

4. An electric post lamp of the class described comprising a flashlight casing, a cap on the upper end of said casing, a platform pivotally mounted on said cap, doll leg members attached to said platform, a support attached to said leg members and disposed thereabove, a doll comprising a torso mounted on the upper end of said support, said support being adapted to retain said leg members and torso in spaced apart relation, an 70 electric light bulb attached to said torso, a reflector mounted on said support, and a skirt attached to said torso and depended over said reflector, said platform being adapted to be adjustably positioned relative to said flashlight casing for retaining said doll and the reflector thereof at a desired inclination to suitably direct rays of light from said bulb.

5. An electric post lamp of the class described comprising a flashlight casing, a doll 85 mounted on said flashlight casing, a reflector disposed beneath the skirt of said doll, and an electric bulb disposed below the torso of said doll and electrically connected with said flashlight casing.

6. An electric post lamp of the class described comprising a flashlight casing, a link pivotally attached to the top of said casing, a platform pivotally mounted on the upper end of said link, a doll comprising leg members 95 mounted on said platform and a torso attached thereto and held in spaced apart relation, an electric bulb disposed below said torso and attached thereto, and a reflector disposed beneath the skirt of said doll, said link 100 being adapted to be positioned at an inclination to said flashlight casing for supporting said doll at an inclination thereto to project rays of light from said bulb sidewise, and said platform being adapted to be disposed substantially horizontal when said link is in inclined position for retaining said doll in substantially vertical position to one side of the center line of said flashlight for directing rays of light vertically downwards at the side 110 of said casing.

In testimony whereof I have affixed my signature.

MIGUEL A. CARVAJAL DE CASTRO.
